United States Patent

Des. 234,393
Patented Feb. 25, 1975

234,393

BOTTLE

Jerome Gould, Los Angeles, Calif., assignor to Stroh
Brewery Company, Detroit, Mich.

Filed Mar. 26, 1973, Ser. No. 344,954

Term of patent 14 years

Int. Cl. D9—01

U.S. Cl. D9—100

FIG. 1 is a perspective view of a bottle showing my new design;

FIG. 2 is an elevational view on an enlarged scale;

FIG. 3 is a top plan view thereof; and

FIG. 4 is a bottom plan view thereof.

I claim:

The ornamental design for a bottle, as shown.
